LIQUOR POURER

James E. McPhee, Culver City, Calif.
Application December 7, 1954, Serial No. 33,426

Term of patent 14 years

(Cl. D58—10)

FIG. 1.

FIG. 2.

FIG. 3.

FIG. 4.

FIG. 5.

Fig. 1 is an elevational view showing one side of a liquor pourer embodying my new design;

Fig. 2 is a front elevational view;

Fig. 3 is an elevational view from the opposite side;

Fig. 4 is a view of the liquor pourer from above; and

Fig. 5 is a bottom plan view thereof.

I claim:

The ornamental design for a liquor pourer, substantially as shown.
